C. UEBELMESSER

FUEL FEED MEANS FOR OIL BURNERS

Filed June 1, 1925

INVENTOR:
Charles Nebelnesser,
BY Leo W. Matth
ATTORNEY

UNITED STATES PATENT OFFICE.

CHARLES UEBELMESSER, OF NEW YORK, N. Y.

FUEL-FEED MEANS FOR OIL BURNERS.

Application filed June 1, 1925. Serial No. 33,982.

My improvements relate to what may be designated as a pre-heating pressure system for feeding liquid hydro-carbon fuel to burners of the type set forth in my concurrent application Serial No. 722,220 filed June 25th 1924, in which vaporization is effected as a preliminary to combustion in a manner well known in a general way in the art as related to the heating of steam boilers, 10 and for analogous purposes, the object of my present invention being to attain more perfect combustion and complete utilization of the calorific value of the hydro-carbon oil used as fuel. Heretofore it has been the practice in the art to pre-heat the fuel oil by means of a pilot light to vaporize the oil preparatory to the starting and operation of the burner, and a separate air pressure system has been essential to the fuel feed. My 20 present improvement consists in the provision of electric pre-heating means, and an automatic pressure system of fuel feed as hereinafter fully set forth,—the invention consisting essentially in the specific combination and arrangement of parts, devices and appurtenances described and claimed.

In the accompanying drawings I illustrate, diagrammatically, a practical embodiment of the essential features of my new 30 system and apparatus as applied to an oil burner of the type designated in my aforementioned concurrent application Serial No. 722,220, although I do not limit myself to the identical form, construction and arrangement of component parts of the system shown by way of exemplification, since changes may be made in minor details, and equivalent mechanical expedients resorted to with like results, and without departing from 40 the spirit and intent of my invention in this respect.

Referring particularly to the left hand portion of the diagram, which shows a top view of a fuel oil burner of the character 45 designated, B, represents the grate plate and b, b, the bars thereof. Interposed between the expansive vaporizing chamber V, and the check valve v^x, and the source of liquid fuel supply v', is the serpentine coil pipe v², extending in circular and substantially horizontal alignment above and parallel to the 50 said grate plate B, the preliminary vaporization of the liquid hydro-carbon fuel being effected in said coil v², and completed in 55 the expansive vaporizing chamber V, pre-

paratory to the introduction of the resultant gas into the grate chamber, as fully set in said concurrent application, the novelty in this connection in the present application, in so far as the burner is concerned, being 60 the interposition in the said vaporizing coil v², of an expansive pressure chamber p, connected by a back pressure pipe p', with an oil supply tank S, p², being a check valve interposed in said back pressure pipe p', 65 adjacent to the said tank S, and between it and a pressure reduction valve r, interposed in said back pressure pipe p', between said check valve p², and the expansion chamber p, said pressure reduction valve r, being connected by a pipe r' with the lower portion of the tank S, as illustrated in the right hand portion of the said diagrammatic view, it being understood that the parts therein shown other than the burner B, and its 70 immediate connections are shown in vertical plane, or substantially so, for convenience of exemplification.

Thus, I, represents a vertical sectional elevation of an initiatory heating tank interposed between the supply tank S, and the burner B, a pipe i, in which is interposed a check valve i', connecting the bottom of said initiatory heating tank I, with the bottom of the fuel supply tank S, and the upper 85 part of said initiatory heating tank I, being pipe-connected with a pressure gauge v.

The induction end v'', of the fuel supply pipe v', extends down axially into the said initiatory heating tank I, and is provided 90 with a hand control valve v¹², for regulating the amount of fuel oil passing through the conduit v', to the burner B, after the fuel feed to the burner is started as hereinafter set forth.

v', is a by-pass pipe connecting the upper 95 part of the initiatory heating tank I, with the main extension of the fuel supply pipe v', and having interposed in it a pressure check valve i'', which yields to admit vapor 100 under pressure from the upper portion of the initiatory heating tank to the burner supply pipe v', but counteracts back pressure from said burner supply pipe v', to the initiatory heating tank I.

Within the latter is positioned an electric 105 resistance coil e, interposed in an electric circuit of which the battery E, or other source of electricity forms a part, e', being a symbolic representation of a switch of 110

well known type controlling the circuit, in which latter is also interposed a spark plug e^2 , positioned with the area of the burner B.

Normally the levels of liquid fuel in both supply tank S, and initiatory heating tank I, are substantially identical owing to the gravity feed therebetween. When it is desired to start fuel feed to the burner B, the hand valve v^{12} , is closed, cutting off temporarily the induction extension v'' , of the burner supply pipe v' , and the electric switch e' , is then closed. As a result, the resistance coil e , in said initiatory heating tank I, raises the temperature of the hydrocarbon oil therein, sufficiently to create vapor under pressure which escapes through the by-pass i^2 , and check valve i^3 , into and through the burner supply pipe v' , to the burner B, where said initiatory vapor escaping through the perforations in the grate bars b, b , is ignited by the spark plug e^2 , after which the hand valve v^{12} , may be opened, and the electric circuit opened also, by means of the switch e' . Under these conditions the feed of liquid fuel is then established through the inductive extension v'' , of the burner supply pipe v' , through the latter to the preliminary vaporizing coil v^2 , and thence to the expansive vaporizing chamber V, and its appurtenances in the burner B, as heretofore.

Vapor pressure incidentally existent in the auxiliary expansive chamber p , is transmitted through the back pressure pipe p' , to the space in the fuel supply tank S, above the liquid level therein, to promote the feed therefrom; and if this back pressure is excessive it is relieved by means of the pressure reduction valve r , and pipe r' , communicating with the bottom of the supply tank S, without interference with the continuous normal feed to the burner B, through the medium of the pipe i , initiatory heating tank I, and feed pipe v' .

It will be seen that distinctive features of my present invention consist in the electrical pre-heating of the preliminary or preparatory feed of fuel to the burner, and in the automatic pressure feed attained by means of the auxiliary expansion chamber p , in the vaporizing coil v^2 , as herein set forth, whereby preliminary vaporization and feed is established expeditiously and with certainty, and a continuous uniform feed insured thereafter, dispensing with the necessity for the supplemental air pressure system of feed heretofore resorted to.

What I claim as my invention and desire to secure by Letters Patent, is:—

1. Fuel feed means for an oil burner of the character designated, comprising a burner provided with a vaporizing chamber and preliminary heating coil connected therewith, an initiatory heating tank the lower portion of which is pipe-connected

with the lower portion of the main oil supply tank, a burner feed pipe connected with the upper portion of said initiatory heating tank and having an inductive end portion extending thereinto, a hand valve connected with said inductive portion of the burner feed pipe, a by-pass pipe and pressure check valve interposed between said burner feed pipe and the upper portion of the said initiatory heating tank, an electric resistance coil in the latter and means for electrically energizing said resistance coil, for the purpose and substantially in the manner set forth. 70

2. Fuel feed means for an oil burner of the character designated, comprising a burner provided with a vaporizing chamber and preliminary heating coil connected therewith, an initiatory heating tank the lower portion of which is pipe-connected 80 with the lower portion of the main oil supply tank, a burner feed pipe connected with the upper portion of said initiatory heating tank and having an inductive end portion extending thereinto, a hand valve connected with said inductive portion of the burner feed pipe, a by-pass pipe and pressure check valve interposed between said burner feed pipe and the upper portion of the said initiatory heating tank, an electric resistance coil 85 in the latter and means for electrically energizing said resistance coil, together with a spark plug positioned in said burner and in parallel electric circuit with the electric resistance coil in said initiatory heating tank, and a switch controlling said electric circuit, substantially in the manner and for the purpose set forth. 90

3. Fuel feed means for an oil burner of the character designated, comprising a 105 burner provided with a vaporizing chamber and a preliminary heating coil connected therewith, an auxiliary expansion pressure chamber interposed in said preliminary heating coil, a back pressure pipe connecting said auxiliary expansion pressure chamber with the upper portion of the main oil supply tank, an initiatory heating tank the lower portion of which is pipe-connected with the lower portion of the main oil supply tank, a burner feed pipe connected with the upper portion of said initiatory heating tank and having an inductive end portion extending thereinto, a hand valve connected with said inductive portion of the burner feed pipe, a by-pass pipe and pressure check valve interposed between said burner feed pipe and the upper portion of the said initiatory heating tank, an electric resistance coil in the latter, and means for electrically energizing 110 said resistance coil, for the purpose and substantially in the manner set forth. 115

4. Fuel feed means for an oil burner of the character designated, comprising a burner provided with a vaporizing chamber and a 120

- preliminary heating coil connected therewith, an auxiliary expansion pressure chamber interposed in said preliminary heating coil, a back pressure pipe connecting said auxiliary expansion pressure chamber with the upper portion of the main oil supply tank, an initiatory heating tank the lower portion of which is pipe connected with the lower portion of the main oil supply tank, 5 a burner feed pipe connected with the upper portion of said initiatory heating tank and having an inductive end portion extending thereinto, a hand valve connected with said inductive portion of the burner feed pipe, 10 a by-pass pipe and pressure check valve interposed between said burner feed pipe and the upper portion of the said initiatory heating tank, an electric resistance coil in the latter, and means for electrically energizing said resistance coil, together with a spark plug positioned in the burner and in circuit with the electric resistance coil in the said initiatory heating tank, and a switch 15 controlling said electric circuit, substantially in the manner and for the purpose set forth.
5. Fuel feed means for an oil burner of the character designated, comprising a burner provided with a vaporizing chamber and a preliminary heating coil connected therewith, an auxiliary expansion pressure chamber interposed in said preliminary heating coil, a back pressure pipe connecting said auxiliary expansion pressure chamber with the upper portion of the main oil supply tank, a pressure reduction valve and pipe connecting said back pressure pipe with the lower portion of said main oil supply tank, an initiatory heating tank the lower portion of which is pipe connected with the lower portion of the main oil supply tank, 20 a burner feed pipe connected with the upper portion of said initiatory heating tank and having an inductive end portion extending thereinto, a hand valve connected with said inductive portion of the burner feed pipe, 25 a by-pass pipe and pressure check valve interposed between said burner feed pipe and the upper portion of the said initiatory heating tank, an electric resistance coil in the latter, and means for electrically energizing said resistance coil, together with a spark plug positioned in the burner and in circuit with the electric resistance coil in the said initiatory heating tank, and a switch 30 controlling said electric circuit, substantially in the manner and for the purpose set forth.
5. Fuel feed means for an oil burner of the character designated, comprising a burner provided with a vaporizing chamber and a preliminary heating coil connected therewith, an auxiliary expansion pressure chamber interposed in said preliminary heating coil, a back pressure pipe connecting said auxiliary expansion pressure chamber with the upper portion of the main oil supply tank, a check valve in said back pressure pipe, a pressure reduction valve and pipe connecting said back pressure pipe with the lower portion of said main oil supply tank, an initiatory heating tank, the lower portion of which is pipe-connected with the lower portion of the main oil supply tank, a check valve interposed in said pipe connection, a burner feed pipe connected with the upper portion of said initiatory heating tank and having an inductive end portion extending thereinto, a hand valve connected with said inductive portion of the burner feed pipe, 40 a by-pass and pressure check valve interposed between said burner feed pipe and the upper portion of the said initiatory heating tank, a check valve in said burner feed pipe positioned adjacent to the burner, an electric resistance coil in said initiatory heating tank, and means for electrically energizing said resistance coil, together with a spark plug positioned in said burner and in parallel electric circuit with said electric resistance coil in the initiatory heating tank, and a switch controlling said electric circuit, substantially in the manner and for the purpose set forth.
5. Fuel feed means for an oil burner of the character designated, comprising a burner provided with a vaporizing chamber and a preliminary heating coil connected therewith, an auxiliary expansion pressure chamber interposed in said preliminary heating coil, a back pressure pipe connecting said auxiliary expansion pressure chamber with the upper portion of the main oil supply tank, a check valve in said back pressure pipe, a pressure reduction valve and pipe connecting said back pressure pipe with the lower portion of said main oil supply tank, an initiatory heating tank, the lower portion of which is pipe-connected with the lower portion of the main oil supply tank, a check valve interposed in said pipe connection, a burner feed pipe connected with the upper portion of said initiatory heating tank and having an inductive end portion extending thereinto, a hand valve connected with said inductive portion of the burner feed pipe, 45 a by-pass and pressure check valve interposed between said burner feed pipe and the upper portion of the said initiatory heating tank, a check valve in said burner feed pipe positioned adjacent to the burner, an electric resistance coil in said initiatory heating tank, and means for electrically energizing said resistance coil, together with a spark plug positioned in said burner and in parallel electric circuit with said electric resistance coil in the initiatory heating tank, and a switch controlling said electric circuit, substantially in the manner and for the purpose set forth.
5. Fuel feed means for an oil burner of the character designated, comprising a burner provided with a vaporizing chamber and a preliminary heating coil connected therewith, an auxiliary expansion pressure chamber interposed in said preliminary heating coil, a back pressure pipe connecting said auxiliary expansion pressure chamber with the upper portion of the main oil supply tank, a check valve in said back pressure pipe, a pressure reduction valve and pipe connecting said back pressure pipe with the lower portion of said main oil supply tank, an initiatory heating tank, the lower portion of which is pipe-connected with the lower portion of the main oil supply tank, a check valve interposed in said pipe connection, a burner feed pipe connected with the upper portion of said initiatory heating tank and having an inductive end portion extending thereinto, a hand valve connected with said inductive portion of the burner feed pipe, 50 a by-pass and pressure check valve interposed between said burner feed pipe and the upper portion of the said initiatory heating tank, a check valve in said burner feed pipe positioned adjacent to the burner, an electric resistance coil in said initiatory heating tank, and means for electrically energizing said resistance coil, together with a spark plug positioned in said burner and in parallel electric circuit with said electric resistance coil in the initiatory heating tank, and a switch controlling said electric circuit, substantially in the manner and for the purpose set forth.

CHARLES UEBELMESSER.
